WIRE BINDING AND TYING MACHINE

Guglielmo Monopoli, Stoke, Nelson, New Zealand

Application August 4, 1932, Serial No. 627,399,
and in New Zealand September 21, 1931

11 Claims. (Cl. 140—93)

This invention relates to an improved machine that has been devised for use in binding packing cases of all kinds and sizes with encircling bands of wire which, after being passed round 5 the case, are strained and have their ends secured by overlapping and twisting them together.

The machine provided by this invention embodies in it the known method of securing the overlapped ends of the wire band together, by 10 the insertion thereof within a radial slot of a rotatable wheel member so that they occupy a position parallel with the member's axis at about the centre of such member, in order that on rotation being imparted to such member, the 15 overlapped ends are twisted one on the other.

This present machine, however, is designed by its special features of construction, to effect an improved tie for securing the band ends together under which a more effective lock between the ends is obtained than by merely overlapping the two ends and twisting them together as has hitherto been the general custom 20 with this class of machine. In this invention a tie is effected by a method under which the wire 25 band has one of its ends doubled back on itself into a long open loop and the other end then brought to overlap the loop so that there are three parallel strands of wire. These three 30 strands are then twisted together for a number of turns (the machine hereinafter described provides for three) so that an effective non-slip grip is exerted by one member upon the other. This method of making the tie is more particularly described in the specification of my current 35 application for United States Patent No. 590,589.

A further feature of this invention is that it will allow for the wire band being drawn from a coil of wire, and then after the band has been passed round the case and the tie effected, 40 for its severance from the coil. Thus the bands may be drawn from the coil, one by one, as each is placed and secured in position upon its packing case, thereby differing from the practice generally hitherto prevailing with this class of band; of using previously cut band lengths. Consequently only enough wire is drawn from 45 the coil to suit the length of band required for the particular size of case in each instance thereby preventing any waste of wire.

50 The invention provides a machine designed to

extend across the case to be bound, and in its operations to receive the end of the wire from the coil as it is passed across the case from one side, and then after the wire has been wrapped round the case and is brought in across it from the opposite side, to double the first end on itself for the required distance and to grip the main portion of the wire and draw it taut across the looped end. It is then adapted to engage the three overlapping wire strands, and to twist them together in the manner described, and at the end of the twisting action, to sever the banded wire from the main length of the coil, and finally to release the band from the machine so that the machine may be removed.

In fully describing the machine and its operations, reference will be made to the accompanying sheets of drawings, in which:—

Figure 1 is a sketch illustrating the method of effecting the banding and the tie.

Figure 2 is a view of the tie itself on a full size scale.

Figure 3 is a plan of the machine, the operating handle being removed.

Figure 4 is a front elevation, and

Figure 5 a back elevation thereof.

Figure 6 is a right hand elevation of the machine.

Figure 7 is a left hand elevation thereof with a part in section.

Figure 8 is an enlarged detail view of a part that will be hereinafter more fully described.

Figures 9, 10, 11 and 12 are cross sectional elevations of the machine, made on the respectively numbered lines in Figure 4 and in each case looking in the direction of the arrow associated with the line of section.

Figure 13 is an enlarged detail view of the twisting member employed.

Figure 14 is an enlarged detail view showing the manner in which the overlapped wire ends are held in the cutting jaws of the machine.

In this invention the machine comprises a frame formed by a flat base block 20 adapted to rest upon a case and having a ledge 21 extending along its forward edge, a plate 22 extending upwardly from the back of the ledge, a bearing 23 for an operating spindle 24 at its right hand end and a vertically disposed gear box 25 near its other end. It also embodies a transversely

55

60

65

70

75

80

85

95

100

extending vertical bearing plate 57 at a distance in from the gear box.

The said gear box 25 contains a set of differential gear wheels disposed on axes parallel 5 with the front edge of the base block 20 and journaled in the sides of such case. This set comprises a pinion 26, fixed on the operating spindle 24, an intermediate gear wheel 27 gearing therewith, and a second pinion 28 geared 10 with the gear wheel. These are made of such ratio that on a fixed number of turns being imparted to the first pinion (three in the arrangement shown) the intermediate wheel 27 will be rotated through a single rotation, while the second pinion 28 will rotate through the same number of turns as the first pinion. This actuation 15 is obtained by carrying the operating spindle 24 beyond the bearing 23 at the right hand end of the base block 20 and providing its end with 20 a crank handle 29, which when the machine is in position upon a case, will be beyond the edge of the case, so that it may be turned freely.

The said second pinion 28 projects at its peripheral edge through the front of the gear case 25, above the ledge 21 of the base block, and is formed with a transverse slot 30 extending radially in to the centre, or slightly beyond, so that wire strands may be laid side by side in the slot 30 and then when the pinion is rotated will be 30 twisted together in a manner already well known in machines for effecting the tying of the wire ends. This pinion is journaled in the sides of the gear box 25 by forming it with journal extensions 31 on both sides, such extensions also 35 having the slot 30 extending along them, as shown in the detail drawing Figure 13.

The intermediate gear wheel 27 has a spindle 32 extending out from the inside of the gear case 25 and through the bearing plate 57 and this 40 is used to operate the wire cutting and other means embodied in the machine, in a manner that will be hereinafter described.

Upon the front ledge 21 of the machine a slide block 33 is mounted to move longitudinally to 45 and fro upon the front of the face plate within limits of movements provided for. A spring 34 controls the block to draw it normally to the left hand end of its movement while it is adapted to be moved to the right by forming its upper face with a toothed rack 35 and journaling a tooth pinion 36 on the aforesaid vertical plate 22 of the frame to gear with the rack 35 so that by the rotation of the pinion 36 in one direction this movement is effected. For so rotating the 50 pinion 36 a lever handle 37 is loosely journaled on the pivot pin 38 of the pinion and to this a pawl 39 is attached by pivoting, such pawl being spring controlled as at 40 to engage the teeth of the pinion to turn it with the lever when 55 the handle 37 is turned in one direction, but to permit of the pinion turning freely beneath the pawl in the reverse direction. This disposal is so made as to provide for the block 33 being moved from left to right and against its spring control, on the actuation of the handle lever, and then when the block is released, for the block sliding back by reason of the pinion having freedom of reverse rotation.

To restrain the block 33 from sliding back 70 when it is thus moved from left to right, it is provided, also on its top, with a ratchet toothed rack 41, and a holding pawl 42 is provided to engage the teeth of the rack and this pawl is mounted on the front of the plate 22 and actuated in a manner hereinafter described.

Upon the front of the sliding block 33 a clamp 80 is provided such clamp being formed by a lower fixed jaw 43 projecting out from the block, and an upper eccentric jaw 44 fixed upon a pivot pin 45 extending transversely through the block from back to front and which jaw is made with a handle 46 for closing it down on to the fixed jaw through the turning action thereof. The pivot pin 45 on which this jaw is fixed, is carried through the sliding block 33 and through a longitudinal slot 75 in the plate 22 of the frame, to the rear thereof to act in conjunction with release apparatus in a manner also herein-after described.

At the extreme left of the base block 20 a transversely extending lever arm 47, shown in enlarged detail in Figure 8, is mounted by pivoting at its rear end to the side of a vertical flange plate 48 upon the base block, so that its forward end may rise and fall, and this lever is spring cushioned as at 49 to normally raise such forward end. This end is made with a forked forward end and with an upwardly extending pin 50 in the lower member of the fork and the forward edge of the flange plate 48 is cut away with a recess or slot 51 extending rearwardly and the said pin projects upwardly across the line of the bottom of this recess and in the front part thereof. Pivoted on the surface of the base block, outside this flange, is a cam block 52 provided with a handle 53 for turning it in the horizontal plane and such cam block is provided with a radially extending arm 54 which when the block is turned in a forward direction from a medial position, will pass from the line 100 of the rear of the pin 50, round across the front thereof and across the front edge of the flange plate 48. The cam block is also provided with an inclined plane 55 on its underside which will when it is turned in a rearward direction 105 from the medial position, pass across the aforesaid pin lever 47 and push it down against its spring 49, so that the pin 50 is depressed beneath the bottom of the recess 51 in the frame flange. 110

In the drawings, Figures 3 and 4, the bending handle is shown as half turned in its bending action the wire being indicated in dotted lines in Figure 3. The handle is also spring controlled so that normally it is swung back a distance to 115 depress the pin 50. This is effected by providing a coiled spring 56 upon the block's pivot the two ends of which are attached respectively to the handle and to the base frame.

The main frame 20 of the machine also embodies a vertical transverse bearing plate 57 the front edge of which is formed with a wire receiving slot 58 extending horizontally across it in alignment with the slot 30 of the pinion 28 and the slot 51 of the flange 48 as also with the 130 clamp 43-44. This slot 58 is furnished with steel lining plates 59 spaced apart one above the other at about the thickness of the band wire. The slot is made to extend inward for a sufficient distance for obtaining the effects hereinafter described.

The bending handle 53 at its extremity, is formed with a laterally projecting fin 60 upon its inner side and this handle is made of such a length that when the handle is turned right 145 in across the front of the machine the fin will enter the said slot 58 and hold within it the wires that may be inserted side by side in the slot in the operations of the machine.

This handle 53 is also formed near its end, 150

on its inner side with a pair of jaws 61 extending one above the other laterally from the handle. The upper jaw is formed on its top with a tooth 62. Mounted on the base 20, in an appropriate position, is a pivoted pawl 63 (shown more particularly in Figure 10) the forward end of which is provided with a tooth on its underside and normally drops downward to an extent limited by the rear end's engagement with the spindle 32 of the gear wheel 27 and in such a position that when the handle 53 is turned round, the tooth 62 engages beneath the pawl and lifts it so that it passes in beneath. The pawl then drops and engages the handle to retain it in such position against the action of its spring 56 tending to swing it back. A cam piece 64 is fixed upon the said spindle 32 to engage the rear end of this pawl, when the spindle is rotated, and to depress such end and raise the forward end to free the handle's engagement with the pawl, so that the handle is then free to swing out and round to its normal position.

On the inner (or right hand) side of the frame plate 57 a vertically moving guillotine knife 65 (shown in Figure 11) is mounted and this is adapted to be depressed by means of a cam lever 66 pivoted at 67, also on this face of the plate, and having a rear extension 68. A cam 69 is fixed on the end of the spindle 32 (which is carried through this plate) which in the turning of the spindle is adapted to engage the end 68 of the cam lever, raising it to depress the forward end 66 and thereby to depress the knife 65. Then as the cam passes on, the lever is released allowing the forward end, and the knife, to be raised.

The knife is kept normally in a raised position by means of the bar 70 that is pivoted to extend longitudinally on the front of the plate 22 of the main frame and at one end to pass through the upper end of the knife frame 71 and then through a vertical slot 72 formed in the bearing plate 57 to receive it. A spring 73 positioned on the other side of the plate and shown in Figure 10, bears upwardly on the end of the bar to force it upward. This bar also extends for a distance, at 70°, on the other side of its pivot and the end of the pawl 42 engaging the slide block ratchet rack 41 (which pawl is arranged loosely on the same pivot) is made to overlie this end and is kept pressed thereon by means of the flat spring 74 (Figure 4). This provides that the pawl may spring upward to permit of the sliding block moving to the right, and then down, to engage the rack 41. It also provides that when the reverse end of the bar 70 is depressed to lower the knife, the pawl 42 is lifted clear of the said rack, to free the sliding block and permit of it moving back to the left under the influence of its spring 34.

The knife 65 is so made and so positioned with respect to the slot 58 that it passes down with a scissor cut across the ends of the steel lining plates 59 thereof and at a distance out from the inner end of the slot sufficiently to clear a wire arranged at the inner end but to engage and cut through one upon its outside. This is shown in the detail Figure 14 of the drawings, where three side by side wires are shown held in the slot by the fin 60 of the bending handle 53, the outmost wire not passing out beyond the cutting edge.

As previously mentioned, the pivot pin 45 of the clamping jaw 44 extends through a slot,

which is shown as 75 in Figures 5 and 12 of the drawings, formed longitudinally in the vertical face plate 22 of the frame so that the slide block 33 is left free to slide to and fro. On the rear end of this pivot pin there is affixed a lever arm 76 which extends radially and is bent so that it loosely confines between its ends a collar 77 that is mounted to slide on a spindle 78 mounted longitudinally in the rear of the machine. This collar is provided with a lifting lever 79 extending forwardly and underlying the said arm 76 in such a manner that the turning of the collar to lift the lever 79 up, will lift the arm 76 to turn the pivot 45 in the direction to open the clamp jaw 44. The collar slides freely on its spindle 78 but is held from rotation thereon and the spindle is free to rotate.

The left hand end of the spindle 78 passes through the bearing plate 57 and upon it, on the right hand side of such plate, is fixed a lever 80 (Figure 11) which normally drops downward to turn the spindle to the position under which the arm 76 of the clamp pivot 45 is free to drop. This lever 80 is arranged in the course of rotation of the cam 69 upon the spindle 32 so that as such moves upward in the rear portion of its travel, it will lift the lever a distance and then permit it to drop, before it passes on to engage and actuate the cutting knife and pawl releasing mechanism previously described. These operations also are arranged to take place, relatively to the release of the bending handle 53, in the rotation of the spindle 32 so that such handle is released as the knife descends to make its cut.

In the operations of the machine, the bending handle 53 is swung back to depress the pin 50. The end A (Figures 1 and 2) of the wire is then brought from the right hand and carried along the machine front, being inserted in the slot 58, the slot 30 of the pinion 28, and through the slot 51 of the flange plate 48. The extremity of the wire is carried then to the point of the fin 60 on the bending handle which acts as a gauge to determine its proper adjustment. The wire is then held by bending the handle 53 back to depress the pin and cause the upper part of the lever 47 to clamp the wire on to the base plate.

The main part C of the wire is then carried round the case and brought in across the machine from left to right, being placed in the front of the slot 51 and then along in the slot 30 of the pinion 28, and through the slot 58, and then into the jaws of the clamp 43-44 to be gripped thereby, the sliding block being then positioned at the extreme left of its movement.

The bending handle is then turned round on its pivot to bend the wire end A round the pin 50 into the open loop form B shown in Figure 1 and to place the outer member of this loop in the slot 30 of the pinion 28 and in the slot 58. This bending is effected by the engagement of the bending arm 54 with the wire and in its wiping action around the front end of the flange plate 48, the wire being held between the jaws 61. The handle then is locked in such position by engagement with the pawl 63 in the manner described.

The sliding block 33 is then actuated by the means provided, to move it to the right so that the main wire is drawn taut around the case and the block locked in the position required, by means of its holding pawl. The looping of the end of the wire round the pin 50 will pro-

vide the hold on such end necessary to effect the strain placed on the wire.

There are thus three overlapping strands of wire in the slot of the pinion 28, arranged side by side. The crank handle 29 is then turned to cause the gear wheel 27 and its spindle 32 to rotate a full turn for three turns of the crank, and the slotted pinion 28 also to turn three times to twist the wires together and to bring the mouth of the slot back to the open position. In the turning of the spindle 32 it will, as it reaches the end of its full rotation, cause, by the operation of the means described, first, the clamp 43—44 to open and release its grip on the wire, will then free the bending handle so that it will turn out and round, under the action of its spring, to depress the pin 50, and following this will depress the cutting knife to sever the band and at the same time free the sliding block 33 from its retaining pawl so that it will slide back to its normal position. The tied band will thus be free to move out of the slots 51, 30 and 58 and the machine may be freed from the band by moving it back, the band sliding out of the several slots. The twisting of the wires in making the tie will effect the requisite straining of the band around the case. As the machine finishes its operation, the various parts are adjusted ready for the next operation.

330 The means for actuating the slide block to move it from left to right in the tautening of the band, may be varied from the mechanism herein described and illustrated in the drawings. It is to be understood therefore that the invention covered is not confined exclusively to the use of such mechanism.

In addition the number of twists to be given the overlapping band members may be varied by varying the ratio of the gear wheels 26, 27 and 28.

I claim:

1. A wire binding and tying machine, comprising a frame, a rotatable member formed with a radial slot across its width extending in to its centre, said member being mounted to rotate in the said frame on an axis longitudinal with the frame's length, a sliding wire clamp mounted on the frame to move to and fro along it on one side of the rotating member, said clamp being provided with means for moving it in each direction, a wire passing along the frame front from the clamp's other end and through the slot in the said rotating member, said wire being received in said clamp, means in the frame upon the other side of said rotating member for permitting a wire end, passing along the frame front from the other end and through the slot in the rotating member and doubled back for a portion of its length, to be again passed into such slot, and means for rotating said rotatable member around its own axis.

2. A wire binding and tying machine, comprising a frame having a base piece, said piece having a vertical longitudinal face plate extending in from one end for a distance, a transversely extending vertical bearing plate near the inner end of such vertical face plate, said transversely extending plate having a horizontal slot at its front end, a vertical flange extending transversely across the base piece near the reverse end from the face plate, said face plate having a horizontal slot in its forward end in alignment with the said slot in the bearing plate, a rotatable member having a radial slot across its width extending in to its centre, said mem-

ber being mounted to rotate on the said frame between the bearing plate and transverse flange, and having its axis longitudinal with the frame's length and in horizontal alignment with the said frame slots, a sliding block mounted on the front of the said face plate to move to and fro longitudinally thereon means for moving said sliding block, and a wire holding clamp fitted on the front thereof, a vertical pin arranged to project upward in the line of the front end of the slot in the said flange and adapted to be raised across the front thereof and to be depressed below it, a bending lever pivoted on the base piece outside the flange for raising and lowering the pin when turned in different directions and having a member projecting therefrom for passing round such pin and across the front of the flange when the lever is turned forwardly.

3. In a wire binding and tying machine according to claim 2, a slotted rotating member formed as a pinion, a gear wheel mounted on a spindle rotating in bearings upon the frame and upon the said bearing plate and gearing with the said pinion, a further pinion geared with the gear wheel, and a power spindle having means for rotating it, which is mounted to extend longitudinally on the frame and upon which the said second pinion is fixed, such gearing being so proportioned as to provide a single complete rotation for the intermediate gear wheel for a fixed number of complete rotations of the two pinions.

4. In a wire binding and tying machine according to claim 2, a gear wheel for conveying rotation to the said slotted rotating member and a spindle upon which it is secured, mounted in the frame and in the said bearing plate, a sliding block having a control spring serving to normally draw it in towards the bearing plate, a ratchet rack upon the sliding block and a pawl pivoted upon the said face plate of the frame to engage such rack to permit of the block moving out against its spring, but to hold it against reverse movement, and cam means operable by the said gear wheel spindle to lift the said pawl at a point in the rotation of the spindle.

5. In a wire binding and tying machine according to claim 2, a gear wheel for conveying rotation to the said slotted rotating member and a spindle upon which it is secured, mounted in the frame and in the said bearing plate, a wire holding clamp upon the said sliding block formed by a lower fixed jaw extending horizontally from the front of the block, an upper eccentric jaw disposed above the fixed jaw, and a pivot pin upon which such upper jaw is mounted that is pivoted in the block and extends through it and through a longitudinal slot formed in the said face plate to receive it, a lever fixed upon the rear end of such pivot, a spindle mounted to extend longitudinally in the rear of the frame, a collar mounted on the spindle to rotate therewith and engaged by the said lever to slide along the spindle with the block's movements, an arm radiating from the collar and underlying the lever, a lever arm fixed upon the spindle, and cam means upon the aforesaid gear wheel spindle for engaging such lever arm at a period in the rotation of the gear wheel spindle, to impart a partial rotation to the collar spindle.

6. In a wire binding and tying machine according to claim 2, a gear wheel for conveying rotation to the said slotted rotating member

- and a spindle upon which it is secured, mounted in the frame and in the said bearing plate, a vertically sliding knife blade disposed against one face of the said bearing plate and adapted 5 to move down across the end of the outer portion of the slot thereof, spring means for keeping such knife normally raised and means for depressing it adapted to be operated by a cam upon the said gear wheel spindle at a point in 10 the rotation of such spindle.
7. In a wire binding and tying machine according to claim 2, a gear wheel for conveying rotation to the said slotted rotating member and a spindle upon which it is secured, mounted 15 in the frame and in the said bearing plate, a bending lever formed on its extremity with an upwardly extending tooth, a spring controlling such lever to normally turn it rearwardly on its pivot, a pawl pivoted on the base piece 20 of the frame to extend transversely thereon in a position to be engaged at its front end by the bending lever end when such is turned in across the frame front and then to drop over the tooth thereof, and a cam upon the said gear wheel spindle 25 engaging the rear of the pawl and adapted to raise its forward end when the spindle turns to one position in its rotation.
8. In a wire binding and tying machine according to claim 2, means for carrying the said 30 vertical pin comprising a lever arm disposed to extend alongside the said flange plate of the frame and pivoted at its rear end to the side of the flange while the vertical pin is attached to or formed upon its forward end, a spring 35 underlying such arm and normally forcing it upward, and a bending lever arm formed with a boss surrounding its pivot the underside of which is made of cam form and overlies the top of the said lever and which cam is adapted 40 when the bending lever is turned rearward, to force the pin lever down, and when turned forwardly, to permit it to rise under its spring action.
9. In a wire binding and tying machine according to claim 2, means for moving the said 45 sliding block comprising a spring for drawing it in an inward direction upon the frame, a pinion mounted freely on the face plate of the frame, a toothed rack along the top of the block 50 with which the pinion engages, a handle loosely mounted on the pinion axis and a spring pawl on such handle that is adapted to engage the pinion and turn it when the handle is moved in one direction but to free it when moved in the 55 other direction.
10. A wire binding and tying machine comprising a frame having a base piece, said piece having a vertical longitudinal face plate extending in from one end for a distance, a transversely 60 extending vertical bearing plate near the inner end of such vertical face plate, said transversely extending plate having a horizontal slot at its front end, a vertical flange extending transversely across the base piece near the reverse end 65 from the face plate, said face plate having a horizontal slot in its forward end in alignment with the said slot in the bearing plate, a rotatable member having a radial slot across its width extending in to its centre, said member being 70 mounted to rotate on the said frame between the bearing plate and transverse flange, and having its axis longitudinal with the frame's length and in horizontal alignment with the said frame slots, a sliding block mounted on 75 the front of the said face plate to move to and fro longitudinally thereon, means for moving said sliding block, and a wire holding clamp fitted on the front thereof, a vertical pin arranged to project upward in the line of the front end of the slot in the said flange and adapted to be raised across the front thereof and to be depressed below it, a bending lever pivoted on the base piece outside the flange for raising and lowering the pin when turned in different directions and having a member projecting therefrom for passing round such pin and across the front of the flange when the lever is turned forwardly, a gear wheel for conveying rotation to the said slotted rotating member and a spindle upon which it is secured, mounted in the frame and in the said bearing plate, a sliding block having a control spring serving to normally draw it in towards the bearing plate, a ratchet rack upon the sliding block and a pawl pivoted upon the said face plate of the frame to engage such rack to permit of the block moving out against its spring, but to hold it against reverse movement, and cam means operable by the said gear wheel spindle to lift the said pawl
